[57] CLAIM

The ornamental design for a handle, as shown and described.

DESCRIPTION

FIG. 1 is a right, top and slightly rear perspective view of a plumbing handle embodying our new design;

FIG. 2 is a right side elevational view thereof, the left side elevational view being a mirror image of the right side shown;

FIG. 3 is a front elevational view thereof;

FIG. 4 is a rear elevational view thereof;

FIG. 5 is a top plan view thereof; and,

FIG. 6 is a bottom plan view thereof.

The broken line representations of a hole in FIGS. 3 and 6, and of a mounting socket in FIG. 6, are for the purpose of illustration only, and form no part of the claimed design.
